SANDER TOOL

Herman T. Opland, Minneapolis, Minn.

Application May 8, 1950, Serial No. 160,610

8 Claims. (Cl. 51—187)

1

This invention relates to a sander tool and especially to the hand type of tool.

The primary purpose of this invention is to provide in a sander tool locking means which quickly and efficiently locks sandpaper to the working surface of the tool, and the locking means also readily releases the sandpaper from its locked position on the tool thus permitting the sandpaper to be quickly removed from the tool.

Heretofore many users of sandpaper merely held the sandpaper in their hand when using the sandpaper for sanding furniture, etc. None of the prior sander tools provided efficient means for either quickly attaching sandpaper to the tool or for quickly detaching the sandpaper from the tool.

It is an object of this invention to provide a sander tool which can be held conveniently in the hand and used without injury to the hand of the operator.

It is another object of this invention to provide means at the opposite ends of a sander tool for temporarily securing sandpaper to the working face of the tool.

It is another object of this invention to provide in a sander tool, locking means for securing sandpaper on the tool and which locking means is mounted inside the body of the tool.

Other and further objects of the invention reside in the detailed construction of the tool which is designed for simplicity and efficiency.

In the following detailed description, reference is had to the accompanying drawing which forms a part hereof. Like numerals refer to like parts in all views of the drawings and through the description.

In the drawings:

Figure 1 is a side elevational view of the sander tool disclosing a sheet of sandpaper secured to the tool.

Figure 2 is a top plan view, parts broken away, of the sander tool.

Figure 3 is a fragmentary side elevational view of the sander tool, parts broken away, and with parts in section.

Figure 4, front elevational view of the sander tool.

Figure 5 is a plan view of the sheet of sandpaper used with the tool.

The improved sander tool 10 consists of a body 12 generally rectangular in shape. The present tool 10 is approximately 5 inches in length, 2 1/4 inches in width and 1 1/2 inches in height, and a tool of such dimensions is easily grasped in the hand of an operator for con-

2

venient use by the operator, but any other desired dimensions may be employed. The lower face or bottom 14 of the tool is flat with a thickness of sponge rubber 14 glued thereto which functions as a pad for the sandpaper 18 mounted over the sponge rubber 16.

A narrow slot 24 is formed in the rear end 31 of the tool 10 and extends from side 28 to side 30. An arcuate groove portion 32 is formed in the top side of slot 24 and extends from side 28 to side 30 of body 10 while a second arcuate groove portion 34 is formed in the bottom side of the slot 24 opposite and coincident with the groove portion 32. An end portion 20 of the sheet 15 of sandpaper 18 extends into the slot 24 and a nail 25 or any other appropriate pointed device is mounted in the arcuate groove 32 in the top of slot 24 and abuts the top side of the end portion 20 of the sheet of sandpaper 18 thus wedging that portion of the end portion 20 of the sheet 15 of sandpaper 18 opposite the shank of the nail 25 into the arcuate groove 34 in the bottom of slot 24 thus wedging or firmly holding the end 20 of the sheet of sandpaper 18 in the rear end 25 of the body 12 of the sander tool 10.

A tubular shaped bore 36 is formed in the body 12 of tool 10 adjacent its front end 29 and extends completely through the body 12. A slot 38 is formed in the front end 29 of the body 12 and communicates with bore 36. A roller 40 slightly smaller in diameter than the tubular bore 36 is mounted for rotation in the bore 36. The roller 40 is formed with a narrow slit 42 and 44 in the ends respectively of the roller 40 with the slits 42 and 44 extending diametrically through the roller and also extending to a central core portion 45 of the roller 40. Oppositely disposed arcuate groove portions similar to groove portions 32—34 in slot 24 are formed in the roller 40 extending from the outer end of slit 42 through core 45 to the outer end of slit 44. A nail 41 is carried in these grooves for a purpose to be set forth hereinafter. A handle 46 square shaped in cross-section is mounted in an aperture extending through the central portion 45 of roller 40. The handle 46 is provided with a slot 47 adjacent its lower end which is for a purpose set forth hereinafter. The outer end of the handle 46 is provided with an approximately 45 degree tapered portion 48 for a purpose hereinafter set forth. A groove 50 formed in the top 33 and front end 29 of the body 12 communicates with the tubular opening 36 and the slot 38 in the front end 29 of the body 12. The rear wall 52 of the groove 50 tapers downwardly from the top 33 of the body

12 to the front end 29 of tool 10. The end 22 of the sheet of sandpaper 18 is notched at 23 providing tab portions 25 and 27.

When the handle 46 is rotated in a counter-clockwise direction the roller 40 is moved to the left until the slits 42 and 44 register with the slot 38 in the front end 29 of the body 12 of sander tool 10, then the tabs 25 and 27 of the sheet of sandpaper 18 can be inserted into the slits 42 and 44 of roller 40 with sides of notch 23 abutting the sides of the core portion 45 of the roller 40. The nail 41 is inserted in one of the oppositely disposed arcuate grooves in the slit 42 in the roller 40 thus securely wedging the end 22 of the sheet of sandpaper 18 in the roller 40. Then the handle 46 is rotated approximately 90 degrees from the position shown in Figure 3 to the right until the side of the handle 46 engages the bottom wall 52 of groove 50 in the top 33 of the body 12 of the sander tool 10. Then the handle 46 is pushed toward the front 29 of the body 12 until the outer end of the handle 46 engages that portion of the bottom wall 52 of the groove 50 positioned on the front side of roller 40 (see Figures 2, 3 and 4) to prevent the roller 40 moving in a counter-clockwise direction for involuntarily releasing the sheet of sandpaper 18 when the tool 10 is being used for sanding an article of furniture etc. The nail 41 extends through the slot 47 in handle 46 for limiting the adjustments of handle 46. When the roller 40 is in the position shown in Figure 1 of the drawings the end 22 of the sheet of sandpaper 18 is wedged tightly between a portion of the wall of the tubular bore 36 and the outer surface of the roller 40 thereby securely holding the sheet of sandpaper 18 in tight engagement with the sponge rubber 18 on the lower face 14 of the body 12.

The sheet of sandpaper 18 may be easily and quickly removed from the tool 10. First the nail 25 is pulled out of the arcuate grooves 32-34 in slot 24 which release the end 20 of the sheet of sandpaper 18. Next the handle 46 is moved rearwardly in groove 50, see Figures 1 and 2, until the lower end of the slot 47 in handle 46 engages the shank of the nail 41 at which time the lower end of the handle 46 disengages the portion of the bottom wall 52 of groove 50 located at the front side of roller 40. Now the handle 46 is rotated in a counter-clockwise direction, see Figure 3, until the slits 42-44 register with the slot 38 in the front 29 of the body 12. Finally the nail 41 is pulled out of the arcuate groove portions in the roller 40 releasing end 22 of the sheet 18 of sandpaper permitting the end 22 to be withdrawn from the slits 42-44 in roller 40 and then pulled out of the slot 38 in the front 29 of the body 12 of sander tool 10.

The handle 46 is of sufficient height so that when the handle 46 is moved to the right (see Figures 1, 2 and 3) until the side of the handle engages the bottom wall 52 of the groove 50 and the handle is pushed forward in groove 50 until the outer end of handle 46 engages the portion of the bottom wall 52 on the front side of roller 40, the tapered portion 48 on the outer end of the handle lies substantially in the same horizontal plane as the top 33 of the body 12 thus no obstructions are on the top of the tool 10 so that the sander tool 10 can be easily grasped in the hand of an operator for use in sandpapering articles of furniture or the like.

A sheet of buff or cloth may be substituted for the sheet of sandpaper 18 and the tool 10 can then be used as a buffer for furniture and the

like. If a length of either buff or cloth should be used with the body 12, then the ends of the cloth would need to be appropriately reinforced or stiffened so that these ends could be conveniently inserted in the slot 24 in the rear end 31 of body 12 and into the slits 42 and 44 in the roller 40 mounted in the bore 36 adjacent the front end of the body 12.

It is contemplated to use different grades of sandpaper with the tool for different types of work.

As can be readily seen, it is easy to secure and remove sandpaper or cloth on the bottom 14 of the tool 10.

Wood is the preferred material for the body of the tool, but the invention is not limited to this particular material as the body of the tool could be formed of either any suitable metallic or non-metallic material.

While a specific form of the improvement has been described and illustrated herein, it is desired to be understood that the same may be varied as to size and shape and different arrangements of the elements of the tool and such changes are deemed to come within the scope of the appended claims without departing from the spirit of the invention.

Having thus described the invention, what is claimed and desired secured by United States Letters Patent is:

1. In a tool of the class described comprising a body including a top, a bottom, a front end and a rear end, the body provided with a bore adjacent the front with a first slot in the front communicating with said bore, a movable means having a handle mounted in said bore, the top and front ends provided with a groove communicating with said bore adapted to receive the handle of the movable means, a stop means mounted in said movable means, the handle provided with a slot in its lower end coaxing with said stop means for limiting the adjustments of said handle in the groove in the top of the body, the rear end of the body provided with a second slot and a wedge carried in the second slot.

2. In a tool of the class described comprising a body including a top, a bottom, front end and a rear end, the body provided with a bore adjacent the front end with a slot in the front side communicating with said bore, a roller having a handle with a tapered outer end, the top provided with a sloping groove communicating with said bore for receiving the handle of the roller, the handle provided with a tapered outer end whereby when the handle actuates the roller toward the rear end of the body until the handle engages the bottom of the sloping groove the tapered outer end of the handle is in substantial alignment with the top of the body.

3. In a hand tool of the class described comprising a body provided with a top, bottom, opposed sides, a rear end, and a front end, a sheet of cleaning material mounted on the bottom of the tool, a roller mounted in a bore in the body adjacent the front end of the tool, the roller being provided with slits, the front end of the body provided with a slot communicating with the bore in the body, one end of the sheet of cleaning material extending through the slot and into the slits in the roller, and means for securing the opposite end of the sheet of cleaning material to the rear of the body, the intermediate portion of the sheet of cleaning material being pulled taut over the bottom of the tool and the portion

of the sheet of cleaning material adjacent the roller being wedged between the roller and the wall of the bore when the roller is moved to a first position in the bore in the body, the slits in the roller being aligned with the slot in the front end of the body when the roller is moved to a second position in the bore whereby the one end of the cleaning material may be released from the slits in the roller.

4. In a hand tool comprising a body of substantially rectangular shape adapted to be held in the hand of an operator, a sheet of cleaning material adapted to be mounted on the bottom of the body, a roller mounted for movement in a bore in the body adjacent the front end of the body, securing means carried by the roller the front end of the body provided with a slot communicating with the bore in the body, one end of the sheet of cleaning material extending through the slot and attached to the roller by its securing means, and means for securing the opposite end of the sheet of cleaning material to the rear of the body, the intermediate portion of the sheet of cleaning material being pulled taut over the bottom of the tool and the portion of the sheet of cleaning material adjacent the roller being wedged between the roller and the wall of the bore when the roller is moved to a first position in the bore of the body, the roller being moved to a second position in the bore in the body whereby the said one end of the sheet of cleaning material may be released from the roller.

5. In a hand tool of the class described comprising a body portion having a slot formed therein in its rear end, the slot in the rear end of the body adapted to accommodate one end of a sanding strip, said body having a cylindrical bore formed therein adjacent its front end, a cylindrical roller mounted for rotation in the bore in the body, securing means carried by the roller, the roller being substantially the same diameter as the bore for tightly fitting in the bore, the front end of the body having a slot communicating with the bore through which the opposite end of the sanding strip extends and the opposite end of the strip fastened to the roller by its securing means, and means for actuating the roller to one position in the bore whereby the intermediate portion of the sanding strip is stretched taut over the bottom of the body portion and the portion of the sanding strip adjacent the roller is wedged between the surface of the roller and the wall of the bore, the actuating means rotating the roller to a second position in the bore whereby the opposite end of the sanding strip may be released from the securing means carried by the roller.

6. In a hand tool of the class described comprising a body portion having a slot formed in its rear end thereof, the slot in the rear end of the body adapted to accommodate one end of a sanding strip, said body having a cylindrical bore formed therein adjacent its front end, a cylindrical roller, mounted for rotation in the bore, securing means carried by the said roller, the roller being substantially the same diameter as the bore for tightly fitting in the bore, the front end of the body having a slot communicating with the bore through which the opposite end of the sanding strip extends and the opposite end of the strip being fastened to the roller by its securing means, and means for actuating the roller to one position in the bore whereby the intermediate portion of the sanding strip is stretched taut over

the bottom of the body portion and the portion of the sanding strip adjacent the roller is wedged between the surface of the roller and the wall of the bore, the said actuating means rotating the roller to a second position in the bore whereby the opposite end of the sanding strip may be released from the securing means carried by the roller, the said body provided with groove means for receiving the actuating means when the roller is moved to said one position in the bore.

7. In a tool of the class described comprising a body including a top, a bottom, a front end and a rear end, the body formed with a bore therein adjacent the front end with a slot in the front end communicating with said bore, a roller means mounted in said bore, the roller having a lateral opening extending therethrough, a handle mounted in said lateral opening in the roller, the handle provided with a longitudinal slot extending from one side to its opposite side adjacent its lower end, a stop means mounted in said roller extending through said slot in the handle for limiting the adjustment of said handle, the top and front end of the body provided with a sloping groove having the greater portion thereof located to the rear of the roller for receiving the handle of the roller, the sloping groove in the top and front end of the body provided with a smaller portion thereof located at the front of the roller for receiving the lower end of the handle when it is pushed through the lateral opening in the roller thereby locking the roller in a predetermined position in the bore, the rear end of the body provided with a second slot.

8. In a tool of the class described comprising a body including a top, a bottom, a front end and a rear end, the body formed with a bore therein adjacent the front end with a slot in the front end communicating with said bore, a roller means mounted in said bore, the roller provided with a lateral opening extending therethrough, a handle mounted in said lateral opening, the top and front end of the body provided with a sloping groove having the greater portion thereof located to the rear of the roller for receiving the handle of the roller, the sloping groove in the top and front end of the body provided with a smaller portion thereof located at the front of the roller for receiving the lower end of the handle when it is pushed through the lateral opening in the roller thereby locking the roller in a predetermined position in the bore, and a second slot in the rear end of the body.

HERMAN T. OPLAND.
